9 Claims. (Cl. 313—84)

1

This invention relates to focussing coils for electron beams.

In cathode ray tubes such as are used for television purposes it is necessary to focus a beam of electrons so as to form a small spot on, for example, the fluorescent screen of the tube. Frequently, such focussing is effected by a multi-layer solenoid of wire through which a suitable electric current is passed, the solenoid surrounding the neck of the cathode ray tube and having an axial length which is at least half the minimum diameter of the solenoid. Such solenoids, however, are found to introduce undesired aberrations into the focussed beam so that, in general, the luminous spot formed on the screen of the tube is not circular nor is it as small as would be possible in the absence of aberrations. Frequently, in order to increase the efficiency of the solenoid an iron sheath is provided which surrounds the solenoid and although the current required to focus the beam is reduced by the use of such a sheath, nevertheless, the presence of the sheath is found to increase the aforesaid aberrations. When a beam of electrons is required to be focussed in cathode ray tubes where great brightness and high resolution are necessary, such as in the so-called projection type of cathode ray tube, it is very desirable that aberrations of focus be avoided as far as possible. If great care is exercised in the winding of the solenoid to ensure uniformity of layering and the prevention of bunching of the conductors, some improvement in performance can be obtained, but even with these carefully wound solenoids some defects in focus still result.

It is believed that the aforesaid aberrations in focussing are due to the flow of components of current parallel to the axis of the solenoid and accordingly the object of the present invention is to provide an improved focussing coil in which an axial flow of current is substantially avoided so as to reduce the above-mentioned aberrations.

According to the invention there is provided a focussing coil for focussing an electron beam and which has an axial length of at least one-half the minimum diameter of the coil wherein the conductor forming the coil is wound in the form of a planar spiral. The coil may be made from metal foil which is wound upon a suitable conducting tubular former and with as many turns as is possible in a given winding space to provide an adequate magnetic field for focussing the cathode ray beam. Instead of employing metal foil, metallised paper or similar material may be used.

2

With a coil made in accordance with the invention the current paths are planar spirals which are all perpendicular to the axis of the coil and there are substantially no components of current parallel to the axis of the coil as is the case with solenoids as heretofore proposed. Such components of current parallel to the axis of the coil are responsible for the aberrations present in the wire-wound solenoids, and these are eliminated by the use of the spiral winding according to the invention.

When a coil in accordance with the invention is used for focussing a very high voltage beam, such as is used in cathode ray tubes of the projection type, a relatively large value of current is required in order to set up a sufficiently large value of ampere turns to produce the required magnetic field. In some cases, however, it may be more convenient to be able to employ a smaller value of current, and to enable such smaller current to be used it is necessary to increase the number of turns employed in the coil. However, if the number of turns of a single planar spiral focussing coil in accordance with the invention is increased, the diameter of the coil may become excessive and, furthermore, the quantity of conductor employed may become uneconomical.

To overcome these difficulties a focussing coil in accordance with a feature of the invention is provided which comprises a plurality of coil units, each in the form of a planar spiral, said coil units being arranged side by side and suitably connected together.

In order that the said invention may be clearly understood and readily carried into effect, it will now be more fully described with reference to the accompanying drawings, in which:

Figure 1 diagrammatically represents a cathode ray tube provided with a focussing coil in accordance with the invention.

Figure 2 is a diagrammatic perspective view of a focussing coil in accordance with one embodiment of the invention.

Figure 3 represents diagrammatically a focussing coil in accordance with another embodiment of the invention and composed of a plurality of coil units.

Figure 4 is a plan view of one way of making the coil units, shown in Figure 3.

Figure 5 is a cross-sectional view taken along the line 5—5 of Figure 4, and

Figure 6 shows the electrical connections of the coil of Figures 4 and 5.

Figure 1 of the drawings illustrates the invention as applied to the focussing of an electron

beam in a cathode ray tube of the type employed for television reception. The cathode ray tube is indicated by the reference numeral 1 and comprises a cathode 2, a cathode screen 3, an accelerating electrode 4, a wall anode 5 and a fluorescent screen 6. The electron beam which emanates from the cathode 2 is focussed into a small spot on the screen 6 by means of a focussing coil 7 which surrounds the neck of the tube 1. In order to overcome the disadvantages hereinbefore referred to when employing the conventional type of wire-wound solenoid coils, the coil 7 in accordance with one embodiment of the invention comprises a strip 8 of aluminium foil of 0.001 inch in thickness and about 2 inches wide and is wound in the form of a planar spiral only a few turns of which are shown in Figure 2, although in practice the coil may, for example, comprise 1500 turns and may be supplied with a current of 1 ampere. The aluminium strip 8 is wound on a conducting former 9 which may consist of a length of copper tubing to which the inner end of the strip 8 is electrically connected. In order to insulate the turns of the foil 8 a paper layer 10 may be employed between adjacent turns although preferably for insulation purposes the surfaces of the aluminium foil 8 are anodised. Instead of employing metal foil, metallised paper or similar material may be employed. In order to provide an adequate degree of focussing the axial length of the coil should be at least one-half the minimum diameter of the coil. The use of a coil as shown in Figure 2 reduces the flow of current parallel to the axis of the coil compared with the case of a wire-wound solenoid having the same axial length and in order to avoid such an axial flow as far as possible with the construction of coil shown in Figure 2, current for energising the coil is supplied thereto by connecting both ends of the former 9 to one terminal 11 of a current source 11 the other terminal of which is connected to the centre point of the outer end of the coil 7 as indicated in Figure 2.

The temperature rise of a focussing coil made as shown in Figure 2 is very much less than in the case of wire-wound solenoids of the same number of ampere turns, since all of the edges of the turns are exposed to air and are able therefore to disseminate heat rapidly. This is an important property since the breakdown voltage of glass falls rapidly with increase of temperature and with existing solenoid coils the glass of the neck of the tube may puncture under the voltages employed in projection types of cathode ray tubes.

As mentioned above, it may in some cases be desirable to employ a small energising current for the coil and in accordance with another embodiment of the invention the use of a smaller current with a reduced diameter of coil can be achieved by employing a construction in which the focussing coil is composed of a plurality of coil units each in the form of a planar spiral suitably connected together. Such a coil construction is illustrated diagrammatically in Figure 3 from which it will be observed that an odd plurality of coil units 12, 13, 14, 15, 16, 17 and 18 are provided, these coil units being arranged side by side and axially along the neck of the cathode ray tube, the units being suitably clamped or held together to form a composite focussing coil. The adjacent coil units are arranged so that the spiral turns are in opposite directions, that is to say, the turns of one unit are arranged in a clockwise direction and the

turns of an adjacent unit are arranged in an anti-clockwise direction. In the arrangement shown in Figure 3, seven coil units are employed and current is supplied to the composite coil by connecting the outermost turn of the central coil unit 15 to one terminal of a current source 11, the current then flowing to the innermost turn of the central unit 15 which innermost turn is connected to the innermost turns of the adjacent units 14 and 16, the outermost turns of such units 14 and 16 being connected to the outermost turns of the units 13 and 17, the innermost turns of these latter units being connected to the innermost turns of the units 12 and 18, the outermost turns of the units 12 and 18 being connected together and to the other terminal of the current source 11. Current thus flows in the directions of the arrows through the various coil units, the manner of interconnecting the various coil units being such that an axial flow of current is reduced to a minimum.

Each coil unit shown in Figure 3 may be wound from wire or narrow tape with the turns suitably insulated from one another and each coil unit may be self-supporting by securing adjacent turns together by means of a suitable adhesive. Alternatively, the turns of each coil unit may be secured to a ring of insulating material and, if desired, opposite sides of said ring may each be provided with a coil unit. The number of turns employed in each coil unit in conjunction with the number of coil units employed can be readily arranged to provide a desired focussing field with a current of a practical value. The composite coil is electrically balanced with respect to the central coil unit and is also radially symmetrical.

Figures 4 and 5 of the drawings illustrate a convenient way of making the coil units and Figure 6 illustrates suitable coil connections for the coils shown in Figures 4 and 5. A ring 19 of insulating material is provided, the ring being composed, for example, of methyl-methacrylate or other suitable plastic and is provided on each side with spiral grooves 20 and 21, one groove being clockwise and the other anti-clockwise, the grooves being then filled with metal as indicated at 22 and 23 for example, copper, by electro-deposition or by any other suitable method. The innermost turn of each spiral groove 20, 21 merges into a concentric groove 24, 25 which, after being filled with metal, provides contact rings 26, 27 for the inner ends of the adjacent coil units. The outer ends of the spirals merge into small contact areas 28 and 29 or, alternatively, said ends can be connected to a suitable contact eyelet 30 attached to the insulating ring 19. Connection between the inner ends of the spirals on adjacent insulating rings is made through the medium of shims or rings of thin metal 32 (as shown in Figure 5) which engage the contact rings 26, 27 when the coil units are clamped together. Insulation between the spirals on adjacent insulating rings 19 is made by means of paper rings 33 or similar material separately applied between adjacent coil units or insulating layers may be applied to the coil units themselves. The coil units on their insulating rings are assembled into a coaxial pile and suitably clamped or held together to form the composite focussing coil. The coil units when made in accordance with Figures 4 and 5 are connected together in the manner shown in Figure 6. In this figure the reference letters A indicate coil units which spiral in a clockwise direction

and the reference letter C coil units which spiral in an anti-clockwise direction. The two centre units C spiral in the same direction so that these two coil units effectively constitute a single unit and hence the composite coil comprises an odd plurality of coil units.

In another method of making a coil unit a ring of suitable thin insulating material, such as a phenolic resin, mica, paper or the like, may be metallised on both sides by securing thereto a thin metal foil or by electro-depositing metal or by providing it with a metal coating in any other suitable manner. The required spiral pattern of the coil, together with suitable contact rings or areas may then be painted, printed or photographically reproduced on to the metallised surface and thereafter unrequired metal areas may be removed in the manner described in the specification of United States patent application No. 690,310. The metallic spiral ultimately formed on said insulating material may be covered with a layer of insulating material as above referred to.

Instead of forming a coil unit in the manner just described, the turns of the spiral may be formed by spraying metal on to an insulating surface through a suitable stencil. Alternatively, a layer of metal applied to an insulating support, such as a layer of foil, may be formed into a continuous spiral by a machining operation by causing a suitable tool to cut away the metal foil so forming a continuous spiral.

I claim:

1. An electron discharge device having a focussing coil for focussing the electron beam of said device, said coil having an axial length of at least one-half the minimum diameter of the coil and comprising a length of conductor arranged in the form of a planar spiral, adjacent turns of the spiral being insulated from one another, and connections between the inner end of said conductor and the outer end of said conductor for feeding current through said coil.

2. An electron discharge device having a focussing coil for focussing the electron beam of said device, said coil having an axial length of at least one-half the minimum diameter of the coil and comprising a length of thin flat conductor having a width equal to the axial length of said coil and arranged in the form of a planar spiral, adjacent turns of the spiral being insulated from one another, and connections between the inner end of said conductor and the outer end of said conductor for feeding current through said coil.

3. An electron discharge device having a focussing coil for focussing the electron beam of said device, said coil having an axial length of at least one-half the minimum diameter of the coil and comprising a length of thin flat aluminium conductor having an anodised surface and a width equal to the axial length of said coil, said conductor being arranged in the form of a planar spiral with adjacent turns insulated from one another by said anodised surface, and connections between the inner end of said conductor and the outer end of said conductor for feeding current through said coil.

4. An electron discharge device having a focussing coil for focussing the electron beam of said device, said coil having an axial length of at least one-half the minimum diameter of the coil and comprising a plurality of coil units arranged side by side, each coil unit comprising a length

of conductor arranged in the form of a planar spiral with adjacent turns of each spiral insulated from one another, and connections between said coil units to reduce an axial flow of current compared with that of a solenoid coil having the same axial length.

5. A focussing coil for focussing an electron beam having an axial length of at least one-half the minimum diameter of the coil and comprising an odd plurality of coil units, each unit being composed of a conductor wound in the form of a planar spiral with adjacent turns of the spiral insulated from one another, said units being arranged side by side with the turns of conductor in one unit arranged in an opposite direction from that of the turns in an adjacent unit, a connection for feeding current to the outer turn of the central unit, connections for feeding current to the outer turns of the outermost units, and connections between the inner ends of the turns of intermediate units and the outermost turns of intermediate units to reduce an axial flow of current compared with that of a solenoid coil having the same axial length.

6. A focussing coil for focussing an electron beam, said coil having an axial length of at least one-half the minimum diameter of the coil and comprising a conducting former, a length of thin flat conductor having a width equal to the axial length of said coil and wound on said former in the form of a planar spiral, means for insulating adjacent turns of said spiral from one another, terminals connected to the inner end of said coil at opposite ends of said former, and a terminal connected to the outer end of said coil.

7. A focussing coil according to claim 6, said latter terminal being connected to the center point of the outer end of said coil.

8. A focussing coil for focussing an electron beam, said coil having an axial length of at least one-half the minimum diameter of the coil and comprising a conducting former, a length of thin flat aluminium conductor having an anodized surface and a width equal to the axial length of said coil and wound on said former in the form of a planar spiral with the innermost turn in electrical contact with said former and with adjacent turns insulated from one another by said anodized surface, terminals connected to the inner end of said coil at opposite ends of said former, and a terminal connected to the outer end of said coil.

9. A focussing coil according to claim 8, said latter terminal being connected to the center point of the outer end of said coil.
